UNITED STATES PATENT OFFICE.

WILLIAM C. KELLY, OF LOUISVILLE, KENTUCKY.

DESIGN FOR AN AX.

SPECIFICATION forming part of Design No. 19,056, dated April 23, 1889.

Application filed February 19, 1889. Serial No. 300,491. Term of patent 14 years.

To all whom it may concern:

Be it known that I, WILLIAM C. KELLY, a citizen of the United States, residing at Louisville, in the county of Jefferson and State of Kentucky, have invented and produced a new and original Design for Axes or Hatchets, of which the following is a specification, reference being had to the accompanying drawing, forming part thereof.

- 10 The leading feature of my design consists of an approximately-triangular-shaped portion of the blade connecting with the head, the remaining portion of the blade being rendered distinctive from the triangular portion.
- 15 That portion contained within the lines $a\ b$ $a\ b$ is raised above and distinctive from those portions contained within the lines $a\ b$, $b\ c$, $c\ a$, as clearly shown in the drawing, which represents a plan or side view of an ax embody-
- 20 ing my design.

The ax shown in the drawing is such a one as forms the subject-matter of an application for Letters Patent filed by me simultaneously herewith and covering the details of construction.

25

What I claim is—

The design for axes herein shown and described, comprising the distinctive central approximately triangular portion contained within the lines $a\ b$ $a\ b$, and the adjacent contrasting portions of the blade connecting with the flat head portion, as shown by lines $a\ b$, $b\ c$, $c\ a$, as set forth.

30 In testimony whereof I affix my signature in presence of two witnesses.

WILLIAM C. KELLY.
